ATTORNEY.

UNITED STATES PATENT OFFICE.

GEORGE W. MACLELLAN, OF LOS ANGELES, CALIFORNIA.

DESIGN FOR A BUTTON, BADGE, EMBLEM, OR SIMILAR ARTICLE OF MANUFACTURE.

54,643.

Specification for Design.

Patented Mar. 9, 1920.

Application filed February 13, 1919. Serial No. 276,871. Term of patent 3½ years.

To all whom it may concern:

Be it known that I, GEORGE W. MACLELLAN, a citizen of the United States, residing at Los Angeles, county of Los Angeles, and the State of California, have invented a new, original, and ornamental Design for a Button, Badge, Emblem, or Similar Article of Manufacture, of which the following is a specification, reference being had to the accompanying drawing, forming part thereof, in which—

The figure is a front view of the button showing my new design.

I claim:

The ornamental design for a button, badge, emblem, or similar article of manufacture as shown.

GEORGE W. MACLELLAN.
